UNITED STATES PATENT OFFICE.

EDWARD R. SARGENT, OF NEW HAVEN, CONNECTICUT, ASSIGNOR TO SARGENT & COMPANY, OF NEW HAVEN, CONNECTICUT.

SLIDING BOLT.

Application filed June 22, 1921. Serial No. 479,632.

This invention relates to sliding bolts for closures and more particularly to a dead bolt which is adapted to be supported in a suitable guide and to be moved into engagement with a guide loop or the like to lock the closure in any desired position. Such bolts are usually mounted to slide freely in their supports and trouble has been experienced with the same when mounted at the top or the bottom of a door, for example, for the reason that they would accidentally fall or slide into locking or unlocking position when such movement was not intended or desired. When such a bolt is mounted at the top of a door to slide vertically into its keeper or guide loop, it would very often fall from the force of gravity to unlocking position. Likewise, when such a bolt was mounted at the bottom of the door, it would be apt to fall accidentally into engagement with its keeper to lock the door closed. Moreover, whether the bolt was mounted to move vertically or horizontally, sufficient play within its mountings has usually been allowed so that the bolt itself often would come in contact with the surface of the door or closure upon which it was mounted to scratch or scar the same. My invention is particularly concerned with overcoming these disadvantages.

One object of my invention is to provide a bolt of this character which shall be so mounted that it will be frictionally held against accidental movement and will at the same time be secured tightly within its mountings to obviate any objectionable looseness.

Another object of my invention is to provide a suitable mounting for a bolt of this character, so that it will be resiliently or yieldably held against looseness or accidental movement, which may be efficient, practical and inexpensive to manufacture.

A further object of my invention is to provide a half-round or flat-sided bolt so as to bring about a more effective engagement between the bolt and the flexible members which are designed to frictionally engage the same.

To these and other ends the invention consists in the novel features and combinations of parts to be hereinafter described and claimed.

In the accompanying drawings:

Fig. 1 is a front elevational view of a bolt embodying the principles of my invention suitably mounted in operative position;

Fig. 2 is a view partly in section along line 2—2 of Fig. 1;

Fig. 3 is a sectional view along line 3—3 of Fig. 1; and

Fig. 4 is a detail perspective view of one of the guides in which the bolt is mounted.

The preferred embodiment selected to illustrate the principles of my invention comprises a sliding or reciprocable bolt 9 suitably mounted in a guide 10 upon a door or other suitable closure 11 and adapted to be moved into engagement with a similar guide 12 mounted upon the door casing 13, the latter guide serving as a keeper, although substantially identical in form with the guide 10. While I have selected a sliding or reciprocable bolt for illustration, it will be understood that the invention in its broader aspects may be applicable to almost any movably mounted bolt.

The bolt 9 may be provided with a suitable knob 14 by which it is adapted to be moved into and out of locking position. It will be noted that the bolt 9 is half-round in cross-section, as shown more particularly in Fig. 3, and is in this manner provided with the flat side or surface 15, which is of particular importance in combination with certain other features of my invention.

The guides 10 and 12, as shown in Fig. 4, consist of a base portion 16, which has an intermediate part 17 struck therefrom to provide a loop. This loop is substantially half-round in shape to correspond with the shape of the bolt in cross-section and is slightly larger than the bolt to permit the latter to move freely therethrough. Upon each side of the loop 17 is left a more or less narrow strip of metal which, as shown, is cut or slit at 18 to provide the two tongues 19 at each side thereof. As is clearly shown in Figs. 3 and 4, these tongues are bent up slightly from the plane of the base 16 of the guide to frictionally engage the lower flat side of the bolt and resiliently urge the same into contact with the upper wall of the loop. The metal from which the guides 10 and 12 are made is preferably of such a character that when the tongues 19 are formed in this manner, they will be slightly resilient in order that the bolt may be frictionally held

against loose play within the loop and yet be readily reciprocably movable within the loop to locking and unlocking position.

The friction resulting from the forcing of the upper rounded surface of the bolt 5 into engagement with the correspondingly shaped surface of the loop and the binding of the bolt between this surface of the loop and the tongues 19 will be sufficient to retain the bolt against accidental displacement or movement either when engaged with both of the members 10 and 12, as shown in full lines in Fig. 1, or when engaged with the guide 10 only and withdrawn from the keeper, as shown in dotted lines in this figure. The tongues 19 are preferably formed upon both sides of the loop 17, so that when the bolt is withdrawn from the keeper and is held in one only of the guides 20 10, it will be effectively retained in position and will not be allowed to swing into contact with the surface of the door or closure member upon which it is mounted. The two points of contact of the tongues 19 upon 25 either side of the loop 17 will effectively maintain the bolt against such swinging motion. It will be apparent, therefore, that while I have provided an effective and efficient means to frictionally and resiliently 30 retain the bolt within its guides against any looseness or accidental movement, at the same time my improved bolt, together with its supporting guides, will be economical to manufacture, so that a practical structure is 35 obtained from the standpoint both of economy and efficiency.

While I have shown and described a preferred embodiment of my invention, it is to be understood that the same is not limited 40 thereto in all of its details, but is capable of modifications and variations which lie within the spirit of the invention and within the scope of the appended claims.

What I claim is:

1. A guide for a movable bolt comprising 45 a base portion, having a guide loop struck up from the intermediate portion thereof whereby a strip of material is left attached to said base portion along each open side 50 of said loop, each of said strips being divided to provide a pair of tongues, said tongues being bent slightly out of the plane at the base portion for the purpose described.

2. A guide member for sliding bolts comprising 55 a base portion, a loop struck up therefrom to provide a passageway for the bolt between the loop and base, a portion of the base at each side of said loop being bent upwardly transversely of the bolt to bear thereagainst and cut or slit longitudinally of the bolt to provide in each portion 60 two opposing tongues, substantially as described.

3. The combination of a sliding bolt of 65 the type described, and means to retain and

guide said bolt, comprising a pair of aligned guides, each having a base portion, a looped portion secured to said base and transversely extending spring fingers adapted to engage the under surface of said bolt and disposed at each open end of said loop. 70

4. In combination, a sliding bolt and a guide for said bolt, having a looped member thereon through which the bolt passes, and an upwardly projecting pair of opposed transverse tongues struck up at each side of 75 said loop member, from the material forming the guide member, to bear against said bolt to retain it in engagement with said loop. 80

5. A guide for a movable bolt, comprising a base portion and a loop struck up therefrom to provide a passageway for the bolt between the base and the loop and a pair of oppositely projecting and transversely 85 extending resilient tongues formed upon the base portion at at least two points in the length of the bolt to bear against the under surface thereof to urge said bolt upwardly and parallel with the surface of said base. 90

6. A guide for a movable bolt, comprising a base having a looped portion thereon through which the bolt passes, and means 95 extending across the mouths of said looped portion and bearing against the bolt to force the same into contact with said loop throughout the length thereof to frictionally retain the bolt in position.

7. A guide for a movable bolt, comprising 100 a base portion having a longitudinally disposed looped portion struck up therefrom, and a pair of opposed upwardly projecting tongues extending transversely across each mouth of said looped portion for the purpose described. 105

8. A guide for a sliding bolt, comprising 110 a base having portions for resting against a support, a loop through which the bolt passes connecting said base portions, and a pair of tongues extending from each 115 of said base portions and slightly bent upwardly out of the plane of said base portions to bear against and frictionally engage the bolt in two places to retain the same in position parallel with the support upon which said base rests within the loop.

9. A guide for a sliding bolt comprising a base portion, a looped portion through which the bolt passes connected to said base portion, and means extending across each mouth 120 of said loop adapted to bear against the bolt to frictionally engage the same and retain it in position within the looped portion throughout the length of said loop.

10. The combination of a sliding bolt, and 125 means to retain and guide said bolt, said bolt being half round in cross-section, said means comprising a pair of aligned guides each having a base portion, a semi-circular looped portion secured to said base, and a 130

pair of transversely extending spring fingers disposed across each open end of said loop, and adapted to engage the flat under surface of said bolt to urge said bolt into contact with the curved inner surface of said loop throughout the length thereof.

11. A guide for a bolt half round in cross section, comprising a base portion having a semi-circular loop portion secured thereto to embrace said bolt, and upwardly springing means disposed across each of the open

ends of said loop beneath said bolt to engage the flat under surface thereof at two points in its length to urge the bolt into contact with the inner surface of said loop 15 throughout the length thereof, whereby said bolt will be retained in parallel with the plane of said base while being moved through said loop.

In witness whereof, I have hereunto set 20 my hand this 21st day of June, 1921.

EDWARD R. SARGENT.
